UNITED STATES PATENT OFFICE.

MANSFIELD C. CRAWLEY, OF GROTON, NEW YORK, ASSIGNOR TO ADDOGRAPH COMPANY, OF LOS ANGELES, CALIFORNIA, A CORPORATION OF CALIFORNIA.

TYPEWRITING MACHINE.

Application filed August 29, 1917, Serial No. 188,774. Renewed March 27, 1923.

To all whom it may concern:

Be it known that I, MANSFIELD C. CRAWLEY, a citizen of the United States, and resident of Groton, county of Tompkins, State of New York, have invented certain new and useful Improvements in Typewriting Machines, of which the following is a specification.

This invention has relation to that type 10 of typewriting machines in which a power motor is employed, and the specific purpose of the present invention is to provide simple means whereby the line-spacing operations may be performed through the medium of 16 said motor to thus relieve the operator of the manual work of performing line-spacing operations, the construction being such that the power devices may be put into operation through the medium of a key in the keyboard 20 as more fully hereinafter set forth.

In the drawings, Fig. 1 is a front elevation of a portion of a platen carriage and the mechanism for rotating the platen for line spacing, parts of the platen carriage being shown in sectional view;

Fig. 2 a horizontal sectional view of a portion of the platen carriage;

Fig. 3 a view similar to Fig. 1, showing the parts in the position which they occupy 30 at the completion of the line spacing action;

Fig. 4 a transverse vertical sectional view of a portion of the platen carriage, taken on the line IV—IV of Fig. 2; and

Fig. 5 is a perspective view of the means 35 for connecting the line spacing device to the shaft.

Referring to the various parts by numerals, 1 designates the drive shaft which is designed to be continuously rotated by any 40 suitable means. Rigidly secured to said shaft is a worm 2. It will, of course, be understood that the drive shaft will be suitably mounted in the typewriter frame. The platen carriage 3 may be supported in the 45 typewriter frame in any suitable manner to permit it to have the usual transverse travel. In the typewriter frame, below the rear part of the carriage is mounted a rock shaft 4, said shaft being provided with forwardly 50 extending substantially horizontal arms 5; and connecting the forward ends of these arms is a transversely extending line space bar 6. In the platen carriage is mounted a transversely extending rock shaft 7 to which 55 is rigidly secured a rearwardly extending

crank arm 8. Connected to the free end of said arm is a depending link 9, which carries a roller 10 at its lower end, said roller being grooved and receiving within said groove the space bar 6. The roller 10 constantly engages and moves upon the lower edge of the line space bar 6, as shown clearly in Figs. 3 and 4. Surrounding the rock shaft 7 is a coil spring 11, one end of which is secured to the rigid support of the rock shaft, the other end being secured to the crank arm 8 and maintaining said arm and the space bar 6 in their upper positions, as shown in Figs. 1 and 4. As the platen carriage moves transversely of the typewriter frame the roller 10 moves along the edge of the space bar, said roller remaining in engagement with the space bar throughout all of the travel of the carriage.

Formed integral with the space bar at the 75 left-hand end thereof is a downwardly and outwardly inclined plate 12, said plate being formed with a downwardly and outwardly inclined slot 13. Mounted upon a rigid bracket 14 is an upwardly extending vertically pivoted post 15, said post carrying at its upper end a forwardly extending substantially horizontal pin 16 which extends through the slot 13 and is provided with an antifriction sleeve which is adapted to engage the upper and lower walls of said slot. The post 15 is provided at its lower end with a forwardly extending arm 17, and on the forward end of said arm is mounted a line space dog 18, said dog being provided at its free end with 80 a depending lug 19 which is adapted to be brought into engagement with the threads of the worm 2. It is manifest that by depressing the dog to bring the lug 19 into engagement with the worm the said lug 95 will be carried transversely toward the center of the machine by the rotation of the worm, thereby turning the post on its pivot and causing the pin 16 to depress the space bar through its connection with the inclined cam surface formed by the lower wall 100 of the slot 13. The slotted plate 12 is curved slightly in order to conform to the arc of travel of the pin 16. It is manifest that by rotating the post 15 and swinging the pin 16 toward the center of the machine the space bar 6 will be drawn downwardly 105 as indicated in Fig. 3 of the drawing. The downward movement of the space bar will rock the shaft 7 through crank arm 8 and 110

link 9. The dog 18 is somewhat loosely mounted on its pivot so that it may have a slight vertical movement, and surrounding its pivot is a spring 20 the free end of which is engaged with a pin 21 on the upper side of the dog. Suitably supported in the frame directly over the worm 2 is a guide plate 22, which is arranged substantially horizontally and is substantially equal in length to the worm. The dog 18 is formed at its inner free end with a rearwardly extending lug 23 which is adapted to engage with the upwardly extending flange 24 of the guide plate when the dog is in its normal or retracted position, as shown clearly in Figs. 1 and 5. The guide plate, adjacent the upstanding stop flange 24, is provided with a slot 25 through which the lug on the dog may pass. The dog 18 is also formed with a forwardly extending lug 26, substantially midway between the ends of the dog as shown clearly in Figs. 1 and 5.

Mounted in the machine frame is a suitably arranged line space lever 27, the finger piece of which may be in any suitable location in the keyboard. At the rear of the machine is pivoted a lever 28 formed with a downwardly extending arm 29 which lies directly over the rear end of the line space lever 27. One arm of the lever 28 is connected to an upwardly extending latch bar 30 whose upper end is adapted to engage the forwardly extending lug 26 of the dog 18. The upper end of the latch 30 is slotted and guided by a pin 31. When the line space key is depressed the upper end of the line space lever 27 is raised, thereby moving the lever 28 and causing the latch 30 to depress the dog 18 and bring the lug 19 thereof into engagement with the worm 2. The downward movement of the dog carries the lug 23 downwardly through the slot in the guide plate 22. When the dog has been sufficiently depressed to bring the lug 19 into engagement with the worm the lug 23 has passed below the guide plate 22 and will ride under said plate until the dog 19 has been carried free of the worm. The lug 23 will be freed from the guide plate 22 the instant the lug 19 is free of the worm. The spring 20 will thereupon lift the dog free of the worm and bring the lug 23 on top of the guide plate 22. As the dog is returned to its normal position the lug 23 rides over the guide plate 22 until it contacts with the stop flange 24, whereupon it will be in a position to again move downwardly through the slot in the guide plate. As soon as the lug 19 is free of the worm the arm 17 is free to return to its normal position. It is manifest that as the spring 11 is constantly tending to lift the space bar 6 the post 15 will be returned to its normal position by means of the cam slot 13 and the pin 16. It is manifest that an upward movement of

the space bar from the position shown in Fig. 3 will rotate the post 15 to the left, thereby withdrawing the dog 18 until its lug 23 contacts with the stop flange 24 of the guide plate. This return movement of 70 the dog will also bring the lug 26 into the path of the latch 30 so that it will be engaged and depressed upon the next operation of the said latch bar.

Rigidly connected to the rock shaft 7 near 75 one end thereof, is an upwardly extending crank arm 32, to the upper end of which is pivoted a forwardly extending pawl 33. The platen 36 is mounted on its shaft 35 which is suitably journaled in the carriage frame and is provided at its ends with the usual hand knobs 37. On the platen shaft 80 is rigidly secured a ratchet wheel 34 which is adapted to be engaged by the forward end of the pawl 33. Pivotedly mounted on the platen shaft, adjacent the ratchet 34, is a swinging gauge plate 38 the rear edge of which is adapted to be brought under the forward end of the pawl 33 to regulate the point of engagement between the said pawl 90 and the ratchet wheel. The gauge plate 38 is adjustable about the shaft 35 so that by varying its position with respect to the head of the pawl 33 the platen may be rotated 95 one or two or more spaces, as desired. Connected to the gauge plate 38 is an upwardly extending operating arm by means of which the position of the gauge plate may be shifted. It is manifest that by adjusting the gauge plate so that the pawl 33 will engage the ratchet wheel near the end of its rearward stroke, the line space mechanism may be adjusted to move the platen one space; and that by adjusting the gauge plate 100 forwardly the distance of one ratchet tooth the platen may be rotated two spaces at each 105 operation of the line spacing pawl 33.

From the foregoing it is manifest that by depressing the line space key the dog 18 will be thrown into engagement with the worm; the line space bar 6 will be depressed and the platen rotated for line spacing through the operation of the link 9, rock shaft 7 and the line spacing pawl. It is also manifest that upon the completion of the 110 line spacing movement all of the parts will instantly return to their normal inactive positions, ready for the next line spacing movement.

It will be observed, therefore, that a feature of importance is that the power mechanism and the line-spacing mechanism shall remain interlocked during a predetermined period of time without regard to what the operator does with the line-spacing key. 115

What I claim is:—

1. A line spacing device for a typewriting machine, comprising a shaft, reciprocable line spacing devices and key-operated means 120 for connecting the said devices to the shaft 130

- independently of the carriage for a predetermined period.
2. A line spacing device for typewriting machines, comprising a platen, a shaft, reciprocal line spacing devices adapted to rotate the platen, and key-operated means for connecting the line spacing devices to the shaft independently of the carriage for a predetermined period.
- 10 3. A line spacing device for typewriting machines, comprising a continuously rotating shaft, a platen, a line spacing device for rotating said platen, key-operated means for connecting said line spacing device with said shaft independently of the carriage for a predetermined period, and adjustable means for varying the extent of rotation of the platen.
- 20 4. A line spacing device for typewriting machines, comprising a continuously operating shaft, a worm thereon and continuously rotated therewith, line spacing devices, and means for temporarily connecting said line spacing devices to said worm.
- 25 5. A line spacing device for a typewriting machine, comprising a continuously operating shaft, a worm thereon, a line space dog, key-operated means for moving said dog into engagement with the worm, and means operated through said line spacing dog to rotate the platen for line spacing.
- 30 6. A line spacing device for a typewriting machine, comprising a continuously operating shaft, a worm thereon, a line space dog, key-operated means for moving said dog into engagement with the worm, means operated through said line space dog to rotate the platen for line spacing, and means for varying the extent of rotation of the platen through the line spacing devices.
- 35 7. A line spacing device in typewriting machines, comprising a continuously operating worm, a line space dog, key-operated means for moving said dog into engagement with said worm, means for maintaining said dog in engagement with said worm for a predetermined distance along said worm, and line spacing devices connected to and operated by said dog.
- 40 8. A line spacing device for a typewriting machine, comprising a continuously operating shaft, a dog, key-operated means independent of the carriage for causing said dog to move longitudinally of said shaft, and line spacing devices connected to said dog.
- 45 9. A line spacing device for typewriting machines, comprising a continuously operating shaft, key-operated means adapted to be brought into engagement with said shaft and to be moved longitudinally thereof through the rotation of said shaft, and line spacing devices connected to said movable means independently of the carriage.
- 50 10. A line spacing device for a typewriting machine, comprising a shaft, means adapted to be moved longitudinally of said shaft for a predetermined distance through the rotation thereof, key-operated devices to cause said means to engage said shaft, and line spacing devices connected to and operated by said movable means independently of the carriage.
- 55 11. A line spacing device for a typewriting machine, comprising a platen, a shaft, means adapted to be moved longitudinally of said shaft for a predetermined distance through the rotation thereof, key-operated devices to cause said means to engage said shaft, line spacing devices connected to and operated by said movable means independent of the carriage, and means for varying the extent of rotation of the platen through the line spacing means.
- 60 12. A line spacing device for a typewriting machine, comprising a platen, a continuously operating worm, a line space dog, key-operated means for moving said dog into engagement with said worm, means for maintaining said dog in engagement with said worm for a predetermined distance along said worm, line spacing devices connected to and operated by said dog, and means for varying the extent of rotation of the platen.
- 65 13. A line spacing device for a typewriting machine, comprising a platen, a line space bar, means connected to said bar and movable longitudinally thereof for rotating the platen for line spacing, a continuously operating shaft, means movable along said shaft and adapted to depress the line space bar, and key-operated means for temporarily connecting the movable means to said shaft.
- 70 14. A line spacing device for a typewriting machine, comprising a platen, a line space bar, means connected to said bar and movable longitudinally thereof for rotating the platen for line spacing, a continuously operating shaft, a worm thereon, a dog adapted to move longitudinally of the shaft, key-operated means for moving said dog into engagement with said worm, and means connected to said dog for depressing the line space bar.
- 75 15. A line spacing device for a typewriting machine, comprising a platen, a line space bar, means connected to said bar and movable longitudinally thereof for rotating the platen for line spacing, a continuously operating shaft, a worm thereon, a dog adapted to move longitudinally of the shaft, key-operated means for moving said dog into engagement with said worm, means connected to said dog for depressing the line space bar, and means for varying the extent of rotation of the platen for line spacing.
- 80 16. A line spacing device for a typewriting machine, comprising a carriage, a platen therein, a line space bar, a continuously

- operating shaft, a worm on said shaft, a line space dog, key-operated means moving said dog into engagement with said worm, means connecting said dog to the line space bar, and means mounted on the carriage and engaging the line space bar to rotate the platen for line spacing.
17. A line spacing device for typewriting machines, comprising a shaft, a worm thereon, a line space dog, key-operated means for moving said dog into engagement with the said worm, a plate to maintain said dog in engagement with said worm for a predetermined distance, means for causing the dog to move over said plate when said dog is released from the worm and return to its normal position, a line space bar, means connecting said dog to said bar to depress said bar as the dog is moved along said worm, a carriage, a platen therein, and means on the carriage connected to the line space bar and operated by the depression of said bar to rotate the platen for line spacing.
18. A line spacing device for typewriting machines, comprising a shaft, a worm thereon, a line space dog, key-operated means for moving said dog into engagement with the said worm, a plate to maintain said dog in engagement with said worm for a predetermined distance, means for causing the dog to move over said plate when said dog is released from the worm and return to its normal position, a line space bar, means connecting said dog to said bar to depress said bar as the dog is moved along said worm, a carriage, a platen therein, means on the carriage connected to the line space bar and operated by the depression of said bar to rotate the platen for line spacing, and means for varying the extent of rotation of the platen through the line spacing means.
19. A line spacing device for a typewriting machine, comprising a platen, a continuously rotating worm, a line space dog formed with a stop lug, a guide plate adjacent said worm and provided with a slot through which the stop lug may pass and with a stop at one end to hold the dog in its normal at-rest position, key-operated means for moving the dog into engagement with the worm and to bring the stop lug thereon under the guide plate, means for lifting the dog above the guide plate when said dog has reached the end of the worm, means for returning said dog to its normal position to bring the stop lug against the stop on the guide plate, and means connecting the dog to the platen to rotate said platen for line spacing.
20. A line spacing device for typewriting machines comprising a continuously operating shaft, a platen, a line space bar, key-actuated means to connect the line space bar to the said shaft to move said bar downwardly and then release it, and means connected to said bar and adapted to engage the platen to rotate it for line spacing.
21. A line spacing device for typewriting machines comprising a continuously operating shaft, a platen carriage, a platen mounted therein, a line space bar, line spacing means on the carriage to engage said bar and move therealong, and key-operated means for temporarily connecting the line space bar to the shaft to move said bar downwardly for line spacing movement.
22. In a typewriting machine, a line-spacing mechanism embodying a ratchet device for rotating the platen and adapted to be actuated at any point in the travel of the carriage, a continuously-driven power shaft, and key-controlled means to connect the line-spacing mechanism with said shaft irrespective of the position of the carriage, means being provided whereby the actuation of the line-spacing mechanism automatically ceases and returns to normal when the line-spacing action is completed irrespective of the position of the key.
23. A line-spacing device for typewriting machines comprising a shaft, means for continuously rotating said shaft, a reciprocable line-space-rail extending the length of travel of the carriage, a platen, means connecting the line-space-rail to the platen whereby the platen may be rotated for line-spacing movements, and key-operated means for connecting the line-space-rail to the shaft.
24. A line-spacing device for typewriting machines comprising a platen, a line-space-rail extending the length of travel of the carriage, means for connecting said rail to said platen to rotate the platen for line-spacing, a power means, and key-operated means connecting the line-space-rail to the power means.
25. A line-spacing device for typewriting machines comprising a platen, a line-space-rail extending the length of travel of the carriage, means for connecting said rail to said platen to rotate the platen for line-spacing, a power means, key-operated means connecting the line-space-rail to the power means, and means for varying the extent of rotation of the platen through the line-spacing means.
26. A line-spacing device for typewriting machines comprising a platen, a ratchet and pawl means for rotating said platen for line-spacing, a continuously-operating power-driven shaft, and key-controlled means for connecting the ratchet and pawl mechanism to said shaft at all points in the travel of the carriage.
27. A line-spacing device for typewriting machines comprising a continuously-operating shaft, a platen, a line-spacing device for rotating said platen for line-spacing, key-

operated means for connecting the line-spacing device with said shaft at all points in the travel of the carriage for giving to said line-spacing means a power movement, 5 and adjustable means for varying the extent of rotation of the platen.

28. In a typewriting machine, a continuously-driven power-shaft, line-spacing means adapted to be operated by said power-shaft, and key-controlled means for putting said line-spacing means into operative connection with said shaft, said line-spacing mechanism embodying a rail-member extending the length of travel of the carriage 10 and a roller-member adapted to relatively 15 travel along said rail during the movement of the carriage.

29. In a typewriting machine, a line-spacing mechanism embodying a ratchet device for rotating the platen and adapted to be 20 actuated at any point in the travel of the carriage, a continuously-driven power-shaft, and key-controlled means to connect the line-spacing mechanism with said shaft irrespective of the position of the carriage, 25 means being provided whereby the actuation of the line-spacing mechanism automatically ceases when the line-spacing action is completed irrespective of the position of the key. 30

This specification signed this twenty-seventh day of August A. D. 1917.

MANSFIELD C. CRAWLEY
